UNITED STATES PATENT OFFICE.

HENRY C. WEEDEN, OF BOSTON, MASSACHUSETTS.

WATER-CLOSET CONNECTION.

SPECIFICATION forming part of Letters Patent No. 297,321, dated April 22, 1884.

Application filed January 12, 1884. (No model.)

To all whom it may concern:

Be it known that I, HENRY C. WEEDEN, of Boston, in the county of Suffolk and State of Massachusetts, a citizen of the United States, have invented certain new and useful Improvements in Water-Closet Connections, of which the following is a specification.

My present invention relates to improvements in the coupling between the flushing-pipe of an earthenware water-closet basin and the metal pipe through which the water-supply is brought, and is illustrated in the accompanying drawings, in which—

Figure 1 shows in elevation an earthenware bowl or closet fitted with my herein-described improvement. Fig. 2 shows a section through the earthenware bowl and coupling device at their point of attachment, and Fig. 3 a similar section at right angles to that of Fig. 2.

Upon the entrance or flushing pipe of an earthenware water-closet basin, A, I form a series of segmental projections, *a*, preferably three in number. I also provide a coupling-piece, B, preferably of brass, provided at one extremity with a reduced externally-screw-threaded part, *b*, the bore of which corresponds to that of the flushing-pipe of the closet. The rest of this part B is cylindrical, of an interior diameter sufficient to pass by the projections *a*, and this cylinder at its upper extremity is provided with turned-in parts *c*. Between these turned-in parts gaps are left substantially corresponding in extent to the extent of the projections *a*, by means of which the cylinder B is enabled to pass the projections *a* when slid onto the end of the flushing-connection in the manner shown in section at

Fig. 2. The sleeve B, having been slid over the earthenware connection, as described, is turned until the parts *c* and the parts *a* are in line. The box or chamber thus formed between the sleeve and the earthenware extension is now filled with a suitable cement or bind, for which I prefer to use sulphur melted and poured in, and the whole is thus firmly and closely united in place. The metallic sleeve B, passing over the exterior of the earthenware connection, serves to strengthen it and protect it from liability to breakage, and the projections or ribs *a* serve to strengthen the joint and to prevent the cylinder B from being accidentally withdrawn.

I am aware that a metallic coupling-piece has been inserted in an earthenware connection, which is recessed to receive it; but this method of construction tends to weaken the earthenware part, instead of strengthening it, and to increase the liability of breakage.

I claim—

The combination, with the flushing-pipe of an earthenware water-closet bowl, A, having the projections *a*, of a metallic surrounding and re-enforcing connection, B, having the reduced screw-threaded part *b* and the inwardly-projecting parts *c*, the whole being cemented and held together by a suitable cement or bind, all substantially as herein specified and described.

In testimony whereof I have hereunto subscribed my name this 5th day of January, A. D. 1884.

HENRY C. WEEDEN.
